UNITED STATES PATENT OFFICE.

PATRICK J. FITZGERALD, OF HAVERHILL, MASSACHUSETTS.

METHOD OF UNITING PIECES OF LEATHER.

SPECIFICATION forming part of Letters Patent No. 352,404, dated November 9, 1886.

Application filed August 26, 1886. Serial No. 211,874. (No model.)

To all whom it may concern:

Be it known that I, PATRICK J. FITZGERALD, a citizen of the United States, residing at Haverhill, in the county of Essex and State of Massachusetts, have invented certain new and useful Improvements in Methods for Uniting Pieces of Leather; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to the utilization of "scrap leather," so called; and it consists in a new and improved method for uniting pieces of leather, by which material hitherto cast one side as almost useless may be again united to 20 form a piece of leather of a size from which may be cut heel-lifts, insoles, or other component parts of a boot or shoe which do not require the best material.

In the accompanying drawings, Figure 1 25 represents a vertical section of two pieces of leather united by my method, while Fig. 2 is a perspective view of a piece of scrap leather with an oblique cut disposed therein to form a scarf-flap. Fig. 3 is a vertical cross-section 30 of the same, and Fig. 4 shows the flap partially turned down. Fig. 5 is a sectional view representing the scarf-flap in position in readiness to be united with another and similarly-prepared piece.

35 The essential feature in my method shown by the above drawings is to enable two pieces of leather to be united by a scarf-joint without materially lessening the size of either piece so united. This is especially important 40 when it is desired to employ "scrap leather," so called, and it will be fully demonstrated hereinafter that in the union of two pieces of leather by my method the superficial area and shape of said pieces after being so joined will 45 remain the same as before, or as if they were butt-jointed.

In the annexed drawings, A represents a piece of scrap sole-leather which it is proposed to unite with some other similarly-prepared piece or pieces, B. Presuming that the 50 edges to be united are square with the surface of the piece, the first step in my process is,

with a suitable knife or skiving-machine, to form along the edge or edges to be united an obliquely-disposed cut, *a*, while the obliquity 55 of said cut may vary, dependent upon whether a long or short scarfed joint is desired. This cut *a* commences upon the upper surface, *b*, of the piece A, extending parallel with the edge *c*, and dips downward and toward the latter 60 surface, but does not reach therethrough. Thus a small strip of material, *d*, is left intact or uncut, and serves to unite with the piece A the scarf-flap C, which has been formed by the knife-cut *a*. Furthermore, it will be observed 65 that the depth of the cut *a* should extend about half through the piece of leather, and in the further completion of my method the front edge, *c*, is divided into two surfaces, 2 3, which are equal in width, and when the scarf-flap C 70 is turned down a continuous evenly beveled or scarfed edge is presented, as shown in Fig. 5, while the said surfaces 2 3 now abut and are brought in close contact with each other, the upper surface of the scarf-flap C being flush 75 with the under surface of the piece A. Similarly the edge or edges of a piece, B, are prepared, and these beveled or scarfed surfaces are, after being coated with some suitable adhesive compound, placed together in the manner shown in Fig. 1, after which they may be 80 heavily pressed to bring the adjoining surfaces more closely in contact and effect a better joint.

In Fig. 1 the abutting surfaces 2 3 upon the 85 individual pieces A B are not aligned, but slightly overlap to make the union of the pieces stronger. Now, the extent of the cut *a* into the leather determines the width of the scarf-flap C, and the scarf-joint is twice the 90 width of said flap. Thus, in lieu of diminishing the size of the leather pieces A B, as is usual in a scarfed joint, by the amount which the ends overlap, said pieces remain of the same size, and in this way scrap leather here-tofore useless may be put together to form one 95 piece of a size suitable for manufacturing purposes. A further advantage is obtained, since the stock is not reduced in thickness, while a smooth even surface is presented upon both 100 sides of the pieces at their point of juncture.

I claim—

1. The method of uniting scrap leather, which consists in the following steps: first

squaring the ends of the scraps to be united, next cutting obliquely into each scrap toward the squared end, so as to form a flap integral therewith, then folding each flap down as a continuation of the scrap to which it is united, and finally imposing the oblique face thus formed of one of the scraps on the other and fastening them together, substantially as set forth. 5

2. The method of uniting scrap leather, 10 which consists in the following steps: first squaring the ends of the scraps to be united, next cutting obliquely into each scrap toward the squared end, so as to form a flap integral

therewith, then folding each flap down as a continuation of the scrap to which it is united, 15 then coating with cement the oblique faces thus formed of the ends of the scraps and placing them in contact with each other, and finally applying pressure to make the cement bind them together, substantially as set forth. 20

In testimony whereof I affix my signature in presence of two witnesses.

PATRICK J. FITZGERALD.
